UNITED STATES PATENT OFFICE.

CHARLES DE VED AND JOSEPH KISSICK, JR., OF NEW YORK, N. Y.

BOILER-TUBE CLEANER.

1,255,988.

Specification of Letters Patent. Patented Feb. 12, 1918.

Application filed February 27, 1914. Serial No. 821,554.

To all whom it may concern:

Be it known that we, CHARLES DE VED, residing in the county of Bronx, city and State of New York, and JOSEPH KISSICK, Jr., residing in the borough of Manhattan, city, county, and State of New York, both citizens of the United States of America, have jointly invented certain new and useful Improvements in Boiler-Tube Cleaners, of 10 which the following is a specification.

Our invention relates to improvements in means for cleaning boiler tubes of water-tube boilers, and is an improvement upon that class of devices employed for said purpose wherein a cleaning fluid under pressure, such as air or steam, is discharged among such tubes for the purpose of cleaning them of accumulations of non-combustible material such as soot, fine ash, etc.

20 Our invention has for its object to provide means which will effectually clean said tubes without preventing the natural draft or passage of the gases of combustion. A further object of our invention is to provide means whereby boiler tubes at varying distances from the source of supply of the cleaning fluid may be cleaned at the same time, and cleaned effectually and efficiently. A still further object of our invention is to provide means whereby the jets of cleaning fluid will not interfere with each other. Another object of our invention is to provide the proper distribution of our nozzles insuring the shortest possible travel of the cleaning jets from the distributing pipes to the surfaces to be cleaned. Another object of our invention is the provision for flexible connections between component parts of a soot clearing system, thus 30 permitting relative movement between the parts, and allowing of ease in installation. These and other objects which will be explained in full as this description proceeds, are accomplished by the apparatus illustrated in the accompanying drawings, and which constitute desirable embodiments of our invention. In the said drawings,

Figure 1 illustrates in side elevation one form of our invention as applied to a type 50 of the Babcock & Wilcox water tube boiler, partly broken away;

Fig. 2 is a cross-section on the line 2—2 of Fig. 1;

Fig. 3 is an enlarged longitudinal sec-

tional view of one of the distributing pipes 55 illustrating the several discharge openings therein, whereby one of the objects of our invention, to wit, the projection of cleaning jets to varying distances, may be accomplished;

Fig. 4 is a cross-sectional detail taken on the line 4—4 of Fig. 2;

Fig. 5 illustrates another application of our invention to a Babcock & Wilcox type of boiler, where the design of baffling calls 65 for a horizontal baffle in some portion of the boiler.

Fig. 6 is a cross-section on the line 6—6 of Fig. 5;

Fig. 7 is an enlarged detail view illustrating a flexible connection between a distributing pipe and a cross header;

Fig. 8 is a similar view illustrating a flexible connection between a cross header and its inlet pipe.

Our invention comprises a distributing pipe A for the cleaning fluid, which may be steam, air or other fluid customarily employed for this purpose, and such distributing pipe we prefer to locate substantially parallel with and next to the tubes of the boiler which are to be cleaned. In a boiler of the type illustrated, we prefer to locate the said distributing pipes above the tubes to be cleaned and next to the said tubes, and by this we mean 75 that the distributing pipes are located next to the group of tubes so that no obstruction is interposed between the pipes and the group of tubes which will prevent the jets of cleaning fluid from reaching the tubes. 80 Although cases might exist where a single distributing pipe would be sufficient for the purpose of accomplishing the object to be attained, it would usually be the case that a plurality of such distributing pipes would 85 be employed, the number of which would depend upon the size of the boiler, number of boiler tubes, etc. We have illustrated the distributing pipes as being located entirely outside the bank or deck of tubes being 90 cleaned, and this is our preferred arrangement. By this disposition the insertion of the distributing pipes is simplified and we are enabled to apply our cleaning system to 95 installed boilers without any change in the arrangement of the tubes. We contrast this with the location of the distributing pipes between or in the midst of the

bank or deck of tubes, which location is troublesome to provide and involves a rearrangement of the boiler tubes to obtain satisfactory results. Furthermore, if such location amidst the deck or bank of tubes involves the substitution of the distributing pipes for one of the boiler tubes, a loss of capacity of the boiler is a further disadvantage which we overcome. These distributing pipes A are connected by suitable means which will be described in detail with a source of cleaning fluid, from which said fluid is supplied under pressure to the distributing pipes. From these distributing pipes the cleaning fluid is discharged among the tubes to be cleaned. One of the parts of our invention consists in the openings through which the said cleaning fluid is discharged. As illustrated in detail view Fig. 3, three types of openings are shown, designated respectively a , a^1 and a^2 . The object to be accomplished by these several different openings is the projection of the jets of cleaning fluid to varying effective distances from the distributing pipe A, so that the effective or cleaning operation of the said jets shall take place at varying distances from the said distributing pipe, thereby enabling each distributing pipe A to clean boiler tubes at different distances from the said pipe. This is accomplished by providing openings at the bores of which are variously shaped at the discharge end, which causes the jets to spread out to a greater or less extent as they are discharged from the distributing pipe. The opening a is as shown a perforation through the distributing pipe A having parallel side walls the length of which is equal to the thickness of the pipe A. The jet of cleansing fluid discharged through the said perforation a will spread out sidewise immediately, as illustrated in dotted lines in the said figure, and will be adapted to clean those boiler tubes which are situated nearest the distributing pipe A, by reason of the fact that the energy in the cleaning fluid is dispersed more or less to the side of the opening a rather than downward. Those boiler tubes which are situated beyond the reach of the jet discharged from the openings a are cleaned by the jet discharged through the straight nozzle illustrated at a^1 . This nozzle is a small section of pipe having a straight bore and threaded into the distributing pipe A. The bore of the said nozzle a^1 is considerably longer than the bore of the opening a and of less diameter, whereby the jet discharged therethrough is caused to spread out to a less extent than that discharged through the opening a , and thereby the said jet is caused to effectively reach and clean boiler tubes situated beyond those cleaned by the jet from a . A jet which carries to a still greater dis-

tance is discharged through an expansion nozzle a^2 , which is a small nozzle threaded into the distributing pipe A and having an annular bore preferably of less diameter than the bore of the nozzle a^1 . The said nozzle flares outwardly toward its delivery or discharge end, as indicated in Fig. 3, whereby the jet discharged therefrom is expanded by having its pressure head converted to velocity head and the increased projective force thereby obtained causes the jet to be projected to a greater effective distance. By proper formation of the discharge nozzle a^2 the designer may within limits mold the jet discharged therefrom in almost any degree to allow of desired dispersion downward and sidewise of said jet. We have illustrated in Fig. 3 the employment of three different types of discharge openings adapted to discharge jets to three different effective distances, but the number of varying discharge openings is shown illustratively merely, as our invention is not necessarily concerned with the provision of three such types of openings. We believe, however, that this will be found to be a desirable number.

The points of discharge are as shown at varying distances from the distributing pipe, whereby the projection of the cleaning fluid to varying distances is assisted.

We have illustrated our invention in connection with a Babcock & Wilcox water tube boiler, although it is not necessarily limited in its employment to such type of boiler, and we have chosen this as a type of boiler extensively employed. In Fig. 1 is illustrated a boiler of such type wherein the tubes B are inclined and are connected to headers C C¹. The gases of combustion pass from the grate D through a path indicated by arrows between the said headers and the baffles E F and bridge wall G. In this type of boiler we believe the tubes will be effectively cleaned by the arrangement of distributing pipes illustrated in Figs. 1 and 2. This type of boiler has several passes for the gases of combustion which we have respectively lettered H, H¹, and H², H being the first pass and H² the last pass, H¹ being the intermediate pass. Our invention provides selective means whereby in a boiler having several passes the tubes in each pass may be cleaned as desired, and it further provides means whereby a portion of the tubes in each pass may be cleaned at the same time, and these selective means are important in that they enable cleaning of the tubes to go on without interference with the natural draft, which effectively carries off the matter dislodged from the tubes, and enables the boiler to continue in service during the cleaning operation. Accordingly our invention provides means whereby if desired tubes may be cleaned throughout their

entire length in the various sections without preventing the passage of the gases of combustion, or a desired number of tubes may be cleaned in one section without preventing such passage and adjacent sections may be cleaned later.

- In Fig. 2 we have illustrated in plan view a desirable arrangement of the cleaning pipes for the Babcock & Wilcox boiler of the type illustrated in Fig. 1. Here the distributing pipes A are illustrated as arranged in four groups which are designated respectively A¹, A², A³, A⁴, and the pipes in each group are connected to respective cross headers I, I¹, I², I³ which are supplied with steam through inlet pipes J, J¹, J², J³. To cross header I there are connected three distributing pipes A¹ which are adapted to clean the tubes at the upper side of the pass H, as viewed in Fig. 2. To the header I¹ there are attached four distributing pipes A² which are adapted to clean the tubes on the lower side of the pass in said figure. There are four distributing pipes A³ connected to the cross header I², and three distributing pipes A⁴ connected to the cross header I³ which are adapted to clean the tubes on the upper and lower side of the said pass respectively.
- Each of these distributing pipes is preferably provided with discharge openings as described which will project the jets of cleaning fluid to varying distances. The boiler tubes are usually arranged in staggered relation as indicated in Fig. 4, whereby by oblique paths lettered K, K¹, L, L¹ are provided between adjacent tubes. The distributing pipes are preferably arranged as indicated in pairs, and each pair of distributing pipes is located as indicated in Fig. 4 above a boiler tube. The several views show that the different discharge openings in each distributing pipe for the cleansing fluid are obliquely arranged with reference to the side walls of the boiler casing. This is so that the discharge openings in each discharge pipe may direct the jet of cleaning fluid through a clear path formed between the boiler tubes from the upper to the lower part. The jets discharged from the various openings in each pipe are preferably discharged in the same direction, so that the said jets will be discharged in the same clear space between the tubes, whereby interference between the jets is prevented and the pipes are effectively cleaned. The distributing pipes are preferably arranged as indicated above alternate boiler tubes, whereby as clearly indicated in Fig. 4 the jets which are discharged in the same direction, as for instance through the several paths K, dislodge the matter from the two sets of tubes between the said jets, and the said matter is carried up by the natural draft of the gases of combustion, which at

that time pass up through the parallel paths K¹. Thereby it is possible if desired to direct the jets in the direction of the paths K upon all boiler tubes in a pass at the same time, and the draft will continue through the paths K¹. It will be observed that the distributing pipes are illustrated as located in pairs, each pair being situated above a boiler tube, and that the openings in the pipes in each pair diverge, whereby those pipes which have their openings arranged in a direction oblique to those already described will direct their jets through the paths or clear spaces between the boiler tubes in a direction to intersect the jets from those described. These intersecting jets follow the paths L as indicated in Fig. 4, and the parallel clear spaces L¹ between the parallel paths L provide for the desired continuance of a natural draft.

It will be seen from the foregoing that the illustrated arrangement of jets provides that a tube is exposed to the cleaning action of two jets whereby it is thoroughly cleaned from all deposited matter, and that with the usual arrangement of tubes a majority of the boiler tubes are so treated.

The middle pass H¹ illustrates the employment of two series or groups of distributing pipes each of which is connected to its own cross header, whereby all the distributing pipes in each group are simultaneously supplied with cleaning fluid. The two groups are respectively lettered A⁵ A⁶ and are respectively connected to cross headers I⁵ I⁶ which are supplied with cleaning fluid through feed pipes J⁶ J⁶. The operation of the pipes in the middle pass is the same as those in the first pass, and they are similarly constructed and direct their jets in a similar manner, and differ from those previously described only in that they are illustrated as divided into two groups which direct their jets along intersecting paths, but which groups are not subdivided as in the first pass. The distributing pipes in the last pass H² are similarly arranged to those in the middle pass.

Means are provided whereby each group of pipes may be separately supplied with cleaning fluid, and such means take the form of stop valves M with which each feed pipe is provided, and whereby the passage of cleaning fluid from the main supply pipe N may be controlled. Where steam is used as the cleaning fluid, upon the shutting down of any of the stop valves M, the feed pipe and distributing pipes are left full of steam which upon condensation forms a partial vacuum in the feed pipe, cross header and distributing pipe, thus sucking in furnace gases and causing the formation of acid with the condensate, whereby the pipes are subject to corrosion. To prevent this we preferably employ a small air vent m which

4
may well be placed in the control valve M. This will be arranged to open when the discharge valve is closed and relieve the vacuum.

5 Our apparatus may also be provided with hand-operated turn cocks O to relieve the pipes of water of condensation, and an automatic drain P may likewise be employed for this purpose. Such devices are well-known 10 and form no part of our present invention, and are therefore not illustrated nor described in detail.

It will be observed that the control valves M are located outside of the casing where 15 they are accessible to the firemen.

A type of boiler frequently employed is illustrated in Figs. 5 and 6 which varies from that previously illustrated in that, because of a variation in design of boiler, the 20 grate D¹ is situated at the lower ends of the boiler, and a portion of the boiler contains a horizontal baffle Q. As the gases of combustion make a sharp turn at the baffle Q, a large amount of soot and ash are thrown 25 down and accumulate on this baffle, and the problem of removing it becomes very difficult. In this case we may prefer to employ in addition to the distributing pipes arranged parallel to the boiler tubes, further 30 distributing pipes extending transversely of the tubes, and adapted to project their jets in varying directions, and such pipes we believe are particularly desirable for cleaning the last pass because of the mechanical difficulties which may prevent the introduction 35 of other methods of carrying and supplying stem jets. For it will be obvious that to discharge jets directly down on a horizontal baffle may cause the soot and ash to accumulate there, and accordingly we have illustrated in Figs. 5 and 6 means for preventing 40 such result. We have illustrated the last pass as being provided with feed pipes R, R¹, R², each having its own controlling valve 45 M, and each of which leads to distributing pipes S which are arranged transversely of the boiler tubes and are perforated for the discharge of the cleaning fluid. The perforations in the pipes preferably open along 50 oblique lines in each pipe so that each pipe is adapted to discharge jets in different directions, as indicated by Fig. 5, and these jets effectively dislodge the deposited matter 55 from the pipes which they reach. The provision of a plurality of such pipes enables us to clean less than the whole of the boiler tubes in the last pass at the same time. It will be observed that each of the feed pipes R, R¹, R² is provided with a number of the 60 transverse distributing pipes S to enable the cleaning of all the tubes in this pass. The pipe R provides a series of transversely 65 arranged distributing pipes S S¹, the upper one of which S¹ extends across the tubes and is arranged so that it will discharge jets

parallel with the tubes, as indicated by the arrows. The first and middle passes are provided with distributing pipes parallel to the tubes, as indicated in Fig. 1. The middle pass is also provided with a transversely arranged distributing pipe S² similar to the pipes S but having its opening adapted to project jets of cleaning fluid as illustrated by dotted lines in said figure, so that the baffle Q will be cleaned and the opening 75 from the middle to the last pass will likewise be cleaned.

There may be some cases where accumulations are liable to occur in the lower part of the first pass H, which cannot be removed 80 by the parallel distributing pipes, and in such cases, generally in boilers where the tubes are spaced in two horizontal banks with an intervening space between equal generally to about 12" to 16", such boilers 85 being known as double-decked boilers, we may employ metal nozzles T as shown to aid in cleaning such tubes, and these nozzles are adapted to direct their jets transversely across said tubes, as illustrated by the arrows 90 in Fig. 6; if desired the discharge openings in the nozzles T may be similarly arranged to the discharge opening of Fig. 3, so as to clean the tubes at varying distances from the side wall. 95

A possible addition to our invention is illustrated in Fig. 5 and in cross section in Fig. 6, and consists of a rotatable distributing pipe V which extends transversely of the superheater W and is rotated by a sprocket 100 chain v gearing in sprocket wheels v¹ v² suitably turned. Pipe V has discharge openings for cleaning fluid which is supplied through feed pipe V¹. By this means the tubes of the superheater are effectively 105 cleaned.

We have also in connection with our invention illustrated means whereby a variation in position or change of position of the parts may be compensated for, and this is 110 accomplished as between the cross headers and the feed pipes by flexible connections between the same. In Fig. 2 at X we have illustrated a looped pipe which furnishes a flexible connection between the cross header 115 I² and its attached distributing pipes A². These are illustrated in detail in Fig. 7. Such flexible connection provides for any relative expansion or contraction of the connected parts and likewise for any inequality 120 in fitting. The connection between the loop X and the distributing pipe is a simple pipe fitting connection. Between the loop X and the cross header I², however, we prefer to provide a swivel connection which will permit of the loop X being turned to accommodate varying distances of connection to the distributing pipe. It is illustrated as turned to a slight extent in Fig. 2. To provide such connection and at the same time 130

preserve a tight joint, the loop X screws into a saddle Y and is held by a jam-nut y in adjusted position, and a bracket y¹ passes around the cross header z² and through perforated ears y² in the saddle, and is held there by nuts, and a gasket y³ is interposed between the pipe and corresponding hole in the cross header to tighten the joint. To provide against any relative movement between the boiler and the setting and to permit an adjustment for fitting a similar loop Z is connected to the cross headers and to the feed pipes after the same have passed through the setting. Such connection is illustrated in detail in Fig. 8 and may be attached to its connected pipe by simple pipe fittings.

Fig. 3 illustrates another connection between a distributing pipe and a cross header which is employed in the middle pass and the last pass of Fig. 2. This connection enables the distributing pipes to be easily removed. It provides a tight joint and likewise permits the distributing pipe to be rotated or turned up and down to proper position. This is somewhat similar to the connection between the distributing pipe and the cross header previously described, and comprises a saddle Y¹ into which the distributing pipe is screwed and held by jam-nut y⁴, and which is attached to the cross header z³ by loop y⁵ which passes through perforated ears in the saddle Y¹ and is there held by nuts. A similar gasket y⁶ is located between the openings in the respective pipes.

Fig. 2 illustrates dummy distributing pipes A¹¹ which are provided to fill the spaces in the brackets A¹² by which the distributing pipes are attached to cross supports A¹³, and enable a stock bracket to be used. Other brackets B¹ pass around the boiler tubes B and through the supports A¹³ where they are held by nuts (Fig. 4).

Our invention has been shown connected to the Babcock & Wilcox boiler wherein the steam generated in the water tubes is collected in the steam drums B² in the usual manner, but such type of boiler is not essential to the employment of our invention, as the same can obviously by the exercise of the skill of the calling be adapted by any capable engineer to other types of boilers such as the Rust or the Stirling or any other water-tube boiler in use.

One of the objects of our invention is stated to be that of producing a cleaning apparatus wherein each cleaning jet traverses the shortest possible distance from its point of emission to the surfaces to be cleaned. This object is accomplished by us by locating our discharge openings, nozzles, jets, etc., in the distributing pipe so that the jets are discharged at right angles to the longitudinal axis of the distributing pipe. Thereby it will be perceived that each jet

traverses the shortest possible distance to the surfaces to be cleaned. This arrangement we contrast with an angled disposition of the discharge orifices whereby the jet is discharged at an angle less than an angle of 70 degrees to the longitudinal axis of the distributing pipe, and accordingly traverses a greater distance to reach the surfaces to be cleaned than is the case with our invention. By means thereof a greater efficiency is secured by our invention. We do not intend to limit ourselves to an arrangement whereby this precise angle of discharge is present, as there may be cases where other arrangements are necessary. But this is our preferred form, and one which we find most efficient.

It is essential to the proper cleaning of a boiler that the draft should not be interfered with and on the contrary should be maintained, not only for the continuance in service of the boiler, but likewise that the dislodged matter may be properly carried off, and it will therefore be apparent that our invention by preventing interference with the draft during the blowing operation; by discharging the jets through the shortest possible distance and by cleaning the complete length of a tube in a pass at one time secures a great increase in heating efficiency and thereby accomplishes an advance over an arrangement whereby the jets are angled with reference to the longitudinal axis of the boiler tubes, so that every part of the clear gas space in a pass of the boiler is reached, by which means it will be apparent the draft is not only restricted but the cleaning operation is rendered ineffectual.

The particular openings in the distributing pipes which are provided for the discharge of the cleaning fluid are for the purpose of enabling said cleaning fluid to be discharged at varying effective or working distances. With the types illustrated it is apparent that the cleaning energy of said fluid is dispersed sidewise and downward in varying degrees. Modifications of the particular discharge openings shown may be made to produce the particular kind of jet desired by the engineer in any boiler and such modifications are esteemed by us within the bounds of our invention.

In the accompanying drawings we have illustrated the application of our invention to a boiler having a single bank or deck of tubes. Boilers have been made having more than one set or bank of tubes superposed, and in such cases our invention can be employed as well as with the single bank or deck illustrated. The employment of the invention in such an installation would involve a substantial duplication of that illustrated, and in such cases the distributing pipes for the lower bank would be located

6
between the several banks or groups of tubes and entirely outside of the bank or group of tubes controlled by such pipes.

We do not regard our invention as being necessarily limited to the particular arrangement of distributing pipes illustrated in the drawings, as it will be apparent that the boiler designer may group these so as to clean various parts of the tubes at his option. There may be any number of groups, and they may be changed with reference to the diagonal spaces between the tubes in some classes of boilers, or by reason of a different variety of boiler header. The foregoing in addition to other changes in construction and arrangement of the parts within the limits of the appended claims, are within our invention.

We claim as our invention—

- 20 1. In an apparatus of the character described, the combination with a water tube boiler having a plurality of boiler tubes of a cleaning system comprising a plurality of stationary distributing pipes located next therewith and one or more distributing pipes carried across the boiler at an angle to the boiler tubes.
- 25 2. In an apparatus of the character described, the combination with a water tube boiler having a plurality of boiler tubes of a cleaning system comprising a plurality of stationary distributing pipes located next therewith and one or more distributing pipes carried across the boiler at an angle to the boiler tubes, said last mentioned distributing pipes being provided with side openings to direct the jets of cleaning fluid between the boiler tubes.
- 30 3. In an apparatus of the character described, the combination with a water tube boiler having a plurality of boiler tubes of a cleaning system comprising a plurality of stationary distributing pipes located substantially parallel to the boiler tubes and a rotatable distributing pipe carried across the boiler, and provided with nozzles to direct the jets of cleaning fluid, and means for rotating said pipe.
- 35 4. In an apparatus of the character described, the combination with a water tube boiler having a plurality of boiler tubes of a cleaning system comprising a plurality of stationary distributing pipes located substantially parallel to the boiler tubes, perforated distributing pipes carried across the boiler setting at an angle to the boiler tubes, one of said distributing pipes being rotatable and means for rotating said pipe.
- 40 5. In an apparatus of the character described, the combination with a water tube boiler having a plurality of boiler tubes of a cleaning system comprising a plurality of stationary distributing pipes located substantially parallel to the boiler tubes, nozzles carried by the distributing pipes, and said distributing pipes having perforations, the whole so disposed that the cleaning fluid may be discharged into the entire length of the clear space between two adjacent sets of boiler tubes in one pass at an oblique angle to the outside wall of the boiler setting at one time, cleaning the entire length of adjacent sets of boiler tubes in said pass at one time, the nozzles in adjacent distributing pipes being inclined relatively to each other, and the perforations being similarly disposed whereby the discharge of cleaning fluid from one distributing pipe is along lines adapted to intersect the line of discharge of cleaning fluid from an adjacent distributing pipe, means for conveying the cleaning fluid under pressure to the distributing pipes and means outside the boiler for controlling the distribution of the cleaning fluid among the distributing pipes.
- 45 6. A distributing pipe for cleaning fluid having openings for the discharge of cleaning fluid, the bores of said respective openings having walls, the axial inclinations of which in the parts thereof leading to the discharge end vary in the different openings in a distributing pipe whereby the said respective openings are adapted to direct the cleaning fluid to different effective distances from the distributing pipe.
- 50 7. In an apparatus of the character described, the combination with a water tube boiler having a plurality of boiler tubes of a cleaning system comprising a plurality of distributing pipes arranged substantially parallel to the boiler tubes, and means for supporting the distributing pipes in pairs above the boiler tubes in such manner that a pair of distributing pipes is located above one boiler tube.
- 55 8. In an apparatus of the character described, the combination with a water tube boiler having a plurality of boiler tubes of a cleaning system comprising distributing pipes arranged substantially parallel with the boiler tubes, a nozzle set in the boiler setting terminating at or near the inside of the boiler setting, means for conveying the cleaning fluid under pressure to the distributing pipes and nozzle and means outside the boiler for controlling the distribution of the cleaning fluid between the distributing pipes and nozzle.
- 60 9. In an apparatus of the character described, the combination with a water tube boiler having a plurality of boiler tubes, of a cleaning system comprising a plurality of distributing pipes approximately parallel with the boiler tubes, a cross header adapted to supply a cleaning fluid under pressure to a plurality of said distributing pipes, means for conveying the cleaning fluid under pressure to the cross header, means outside the cross header, means outside the boiler for controlling the distribution of the cleaning fluid between the distributing pipes and nozzle.
- 65 10. In an apparatus of the character described, the combination with a water tube boiler having a plurality of boiler tubes, of a cleaning system comprising a plurality of stationary distributing pipes located substantially parallel to the boiler tubes, nozzles carried by the distributing pipes, and said distributing pipes having perforations, the whole so disposed that the cleaning fluid may be discharged into the entire length of the clear space between two adjacent sets of boiler tubes in one pass at an oblique angle to the outside wall of the boiler setting at one time, cleaning the entire length of adjacent sets of boiler tubes in said pass at one time, the nozzles in adjacent distributing pipes being inclined relatively to each other, and the perforations being similarly disposed whereby the discharge of cleaning fluid from one distributing pipe is along lines adapted to intersect the line of discharge of cleaning fluid from an adjacent distributing pipe, means for conveying the cleaning fluid under pressure to the distributing pipes and means outside the boiler for controlling the distribution of the cleaning fluid among the distributing pipes.

boiler for regulating the supply of the cleaning fluid to the cross header, and an automatic air relief apparatus outside the boiler to admit a protective stream of air into the cross header.

10. In an apparatus of the character described, the combination with a water tube boiler having a plurality of boiler tubes, of a cleaning system comprising a plurality of distributing pipes arranged substantially parallel with the boiler tubes, a cross header adapted to supply a cleaning fluid under pressure to a plurality of said distributing pipes, and a flexible connection between the distributing pipes and the cross header allowing adjustment of the distributing pipes in relation to the cross header.

11. In an apparatus of the character described, the combination with a water tube boiler having a plurality of boiler tubes, of a cleaning system comprising a plurality of distributing pipes substantially parallel with the boiler tubes, a cross header adapted to supply a cleaning fluid under pressure to a plurality of said distributing pipes, means for conveying the cleaning fluid under pressure to the cross header, and means outside the boiler to regulate the supply of cleaning fluid to the cross header.

12. In an apparatus of the character described, the combination with a water tube boiler having a plurality of boiler tubes, of a cleaning system comprising a plurality of distributing pipes in each pass, said pipes extending approximately parallel with the boiler tubes, and a plurality of cross headers in a pass adapted to convey a cleaning fluid under pressure to the distributing pipes, each of said cross headers being connected to a part of the distributing pipes in a pass and means whereby the cleansing fluid may be supplied to each cross header as desired, whereby part of the tubes in each pass may be cleaned simultaneously and the free passage of the gases of combustion may be permitted between the remaining tubes.

13. In an apparatus of the character described, the combination with a water tube boiler having a plurality of boiler tubes and a cleaning system comprising sectional means inside the boiler setting for distributing the cleaning fluid under pressure over the surface to be cleaned, means outside the boiler setting for controlling the distribution of the cleaning fluid under pressure to the various sections of the apparatus inside the boiler setting as desired, and flexible means for connecting the parts of the system inside the boiler setting to the parts of the system outside the boiler setting.

14. In a water tube boiler having a plurality of boiler tubes and having the path for the products of combustion divided into

passes by baffle plates and boiler headers, means for cleaning the boiler tubes, comprising a plurality of distributing pipes in a pass, said pipes located substantially parallel with the boiler tubes, and having discharge openings, said distributing pipes being divided into groups in a pass, and means for supplying the respective groups with cleaning fluid as desired, whereby a part of the tubes in a pass may be cleaned at a time without interference with the draft.

15. In a boiler having a plurality of water tubes provided with partitions for providing a plurality of passes for the gases of combustion, means for cleaning said tubes comprising a plurality of distributing pipes in each pass, said pipes located substantially parallel with the tubes and having discharge openings, a cross header for the distributing pipes in each pass, and means for supplying cleaning fluid to each cross header.

16. In a boiler having a plurality of water tubes provided with partitions for providing a plurality of passes for the gases of combustion, means for cleaning said tubes comprising a plurality of distributing pipes in each pass, said pipes located substantially parallel with the tubes and having discharge openings, the distributing pipes in each pass being separated into groups, a cross header for the distributing pipes in each group, and means for supplying cleaning fluid to each cross header.

17. In a boiler having a plurality of water tubes provided with partitions for providing a plurality of passes for the gases of combustion, means for cleaning said tubes comprising distributing pipes located substantially parallel with the tubes and having discharge openings, the distributing pipes in each pass being separated into groups, the openings in each pipe of a group of pipes directed in the same direction and obliquely to the side wall of the boiler setting, and the other pipes in said group of pipes provided with corresponding openings but adapted to direct jets along lines which intersect those of the first-named group, and means for supplying cleaning fluid to each group of pipes separately.

18. In a boiler having a plurality of water tubes provided with partitions for providing a plurality of passes for the gases of combustion, means for cleaning said tubes comprising distributing pipes located substantially parallel with the tubes and having discharge openings, the distributing pipes in each pass being separated by groups, the discharge openings in said pipes directed obliquely to the side walls of the boiler setting and the openings in the pipes in a group adapted to direct jets along lines adapted to intersect the line of jets from

the pipes in another group and the respective pipes in each group located adjacent alternate boiler tubes, and means for supplying cleaning fluid to each cross header.

5 19. In a water tube boiler having a plurality of boiler tubes, a cleaning pipe located substantially parallel to the boiler tubes, having openings for the discharge of cleaning fluid comprising nozzles; different 10 nozzles in a pipe adapted to project jets of cleaning fluid to different distances, whereby tubes at different distances from the same distributing pipe may be simultaneously cleaned.

15 20. In a water tube boiler having a plurality of boiler tubes, a plurality of cleaning pipes located substantially parallel to the boiler tubes, having openings for the discharge of cleaning fluid, comprising nozzles, 20 different nozzles in a pipe adapted to project jets of cleaning fluid to different distances whereby tubes at different distances from the same distributing pipe may be simultaneously cleaned, and said nozzles adapted to 25 project said jets through the clear space formed between adjacent rows of tubes.

21. In a water tube boiler having a plurality of boiler tubes, a plurality of cleaning pipes located substantially parallel to the 30 boiler tubes, having openings for the discharge of cleaning fluid, comprising nozzles and perforations adapted to project jets of cleaning fluid to varying distances, whereby tubes at different distances from the same 35 distributing pipe may be simultaneously cleaned and the nozzles and perforations in each distributing pipe adapted to project their jets through the same clear space and the jets from adjacent pipes being projected 40 along intersecting lines.

22. In combination a boiler having water tubes arranged in rows, and means for cleaning said tubes, comprising a distributing pipe for the cleaning fluid provided with a 45 plurality of discharge orifices, said orifices being variously shaped, said variously shaped orifices being adapted to project jets of said fluid down the interval between the rows of tubes to varying effective distances 50 from said pipe.

23. In a boiler having water tubes, means for cleaning said tubes comprising a distributing pipe for the cleaning fluid, said pipes having discharge openings having 55 their delivery ends at varying distances from said pipe whereby the jets are caused to project to varying effective distances from said pipe.

24. In a boiler having water tubes, means 60 for cleaning said tubes comprising a distributing pipe for the cleaning fluid; discharge nozzles in said pipe having their bores near the delivery end of different

shapes longitudinally whereby jets of cleaning fluid are caused to be projected by the same pressure to varying effective distances.

25. In an apparatus of the character described, the combination with a water tube boiler having a plurality of tubes, of means for cleaning the tubes comprising a plurality of distributing pipes located substantially parallel with the said tubes, each of said pipes having perforations for the discharge of cleaning fluid, and the said perforations adapted to discharge jets from a distributing pipe along lines which intersect the lines of jets discharged from other pipes.

26. In an apparatus of the character described, the combination with a water tube boiler having a plurality of tubes of means 80 for cleaning the tubes comprising a plurality of distributing pipes located substantially parallel with the said tubes, each of said pipes having perforations for the discharge of cleaning fluid, and the said perforations 85 adapted to discharge jets along intersecting lines, and said distributing pipes each extending throughout the heating length of a tube in a pass.

27. In an apparatus of the character described, the combination with a water tube boiler having a plurality of tubes, of means for cleaning the tubes comprising a plurality of distributing pipes located substantially parallel with the said tubes, each of 95 said pipes having perforations for the discharge of cleaning fluid, and the said perforations adapted to discharge jets along intersecting lines, and said distributing pipes each 100 extending throughout the heating length of a tube in a pass and means whereby a portion only of the distributing pipes in each pass may be supplied with cleaning fluid at one time.

28. In a boiler having a plurality of water 105 tubes staggered relatively to one another whereby clear spaces are formed between diagonal lines of tubes in each direction, means for cleaning said tubes comprising distributing pipes substantially parallel with 110 said tubes and located in pairs substantially above alternate tubes, each pipe having discharge openings obliquely arranged relative to a vertical line, whereby each pipe is adapted to direct its jets through alternate 115 clear spaces, and the intermediate clear spaces permit the draft to continue.

In witness whereof, we have hereunto signed our names in the presence of two subscribing witnesses.
